(57) **CLAIM**

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a top plan view thereof;

FIG. 4 is a bottom plan view thereof;

FIG. 5 is a side elevational view thereof from the left of FIG. 2; and,

FIG. 6 is a side elevational view thereof from the right of FIG. 2.

The material shown in broken line indicates one possible environment in which the present invention may be used, but forms no part of that invention.
